UNITED STATES PATENT OFFICE

FREDERICK M. HILL, OF WESTMONT, ILLINOIS, ASSIGNOR TO THE RAILROAD SUPPLY COMPANY, OF CHICAGO, ILLINOIS, A CORPORATION OF ILLINOIS

INTERLOCKING RELAY

Application filed May 9, 1927. Serial No. 189,860.

The invention pertains to a signalling system, and more particularly to an interlock which will only operate while a train is entering and passing a crossing, regardless of the position of other signalling blocks adjacent the crossing.

It is common practice to provide a signal such as a bell, semaphore, flashing lights, etc. at a grade crossing, together with a relay energized from any convenient source of current to hold open the switch controlling said signal. According to such prior structures, it was common to have the metal of a car truck shunt the source of current whereby the switch controlling the signal was allowed to operate, and in such a system, the signal continued to operate until the rear of the train had passed the crossing and the succeeding block. It will therefore be seen that there was a continuous and unnecessary operation of the signal after the train had passed the crossing, which is decidedly undesirable as it causes disrespect for the signal.

It is therefore an object of this invention to provide a relay of simple, effective, flexible and inexpensive character, to make and maintain, whereby a warning signal will not operate after the train has passed the crossing.

Another object is to provide interengaging gravity latches for a relay which will allow operating members of the relay to function but will insure that no signal is given after a train has passed a crossing.

A further object is to provide a relay of such character that if a part of the system should fail, the crossing signal will still operate as a warning.

A still further object is to provide an electric relay controlled by a train entering a block to actuate a signal but which prevents continued actuation of said signal when the train has left the block and passed the crossing.

Other and more specific objects will occur from the detailed description and drawings appended hereto.

In the drawings, wherein like reference characters are used to designate like parts—

Figure 1 is a diagram of a plurality of

blocks of a railroad, showing the hookup of the relay with said blocks;

Figure 2 is an elevation of a relay device made up of a plurality of actuating units controlled by the relay latches;

Figure 3 is a sectional plan of a portion of the device shown in Figure 2 taken substantially on the line 3—3 of Figure 2; and

Figure 4 is an elevation of one of the locking latches for controlling the signal.

Referring particularly to the form of the device shown in Figures 2 and 3, the device may for descriptive purposes be conveniently divided into two parts, which parts are controlled by a train entering adjacent blocks. In the embodiment shown, solenoids 5 and 5', shown as a double unit each made up of individual solenoids 5a and 5b, support a platform member 11 carrying binding posts 10 which are adapted to be connected to the rails of their particular block. As already pointed out, this device is made up of a plurality of units so it will only be necessary to describe one unit, it being understood that similar parts of the device are of the same construction and for similar use.

The solenoids 5 may be supported from any convenient base 28 which is suitably connected or supported by a base 27, between which bases the moving parts of the relay may be conveniently disposed. Between the bases 28 and 27, there may be hinged along an axis as indicated at X—X, the contact member 6 made up of a plurality of fingers 6a, 6b, etc., and the similar member 6' also made up of fingers 6'a, 6'b, etc. The member 6 is provided with contact fingers 15 which are adapted to alternately contact the post 13, and the post 14 which may have a portion surrounding but not contacting the arm 6a, and which member 14 has an upstanding post or finger 30 adapted to have contact with the finger 15 when said finger is in lowered position.

Metal bars or saddles 29 are adapted to straddle the contact members 6 and 6' beneath the solenoids. These members may each conveniently carry an insulated arm 19 bent to a convenient shape, to be disposed to

actuate the latches 20 and 21. These latches 20 and 21, which form the important part of this invention, are pivoted at 23 and 23' and are adapted to be actuated toward each other by the members 19. These latches may conveniently be carried on a bracket 25 which is adjusted by means 26 and 26', said latches comprising a shank terminating in an arcuate edge 22 terminating in a toe, the edge of one latch providing a blocking means for the toe of the other latch when the first-named latch is operated. The latch also is provided with a shoulder 24 adjacent the pivot, substantially at right angles to the shank of the latch and disposed in way of the operating bar 19.

As already pointed out, the other side of the relay is exactly the same; that is, fingers 6'a and 6'b correspond, respectively, to the fingers 6a and 6b, and the posts 13' and 14' correspond to the posts 13 and 14 respectively.

The device is conveniently hooked up to the track circuit as follows: As this device is made up of a plurality of units, each of which may independently operate its respective latch, it is only necessary to describe the hook up of one arm, for instance, 6a and 6'a of each side of the relay, as it will be understood that the other arms of the units may be hooked up in a similar way to other blocks to operate the signal. The solenoid 5, as seen in Figure 1, is hooked up to one block A of the track 1, through the posts 10, said track having two blocks wherein the points 3 designate insulated joints in the track. The other solenoid 5' is attached in a similar manner to the block B. It will, of course, be understood that the middle insulating point 3 designates the crossing.

These solenoids 5 and 5' are constantly supplied with current from any source 4 and 4', respectively, attached to the respective blocks A and B. The contact members 6 and 6' are attached through one post leading to 17 and 17', respectively, to a current source or battery 9, the other post of said battery being fastened to a post of the signal 8. The posts 13 13', which are adapted to be contacted by fingers 15 of the contact members 6 and 6' when the solenoids are in energized position, may be connected to any line and run to any device which is actuated by intermittent current, it being understood that for the purposes of this invention, these posts might just as well have been left off as far as the actuation of the signal by the relay is concerned. The contact members 7 and 7' are adapted to be attached through the posts 14 and 14' to the other post of the signal 8, as indicated in Figure 1.

When the train is entering block A, coming from the left as indicated by the arrow of Figure 1, the locomotive truck as soon as it enters this block will shunt the current of the

left hand battery 4, which will cause the solenoid 5 to become deenergized and will allow the contact member 6 to drop, causing the arm 19 through its contact with the shoulder 24 to partially revolve the latch 20 in a blocking position to the latch 21, as shown in Figure 2. When the arm 6 drops, it will, of course, break contact with post 13 and make contact with the post 14. In other words, the contact member 6, referring to Figure 1, will come in contact with the contact member 7, closing the circuit and causing the signal to actuate. As the train continues to the crossing, and as the forward locomotive trucks enter the block B, the solenoid 5', through similar shunting of the battery 4', will become deenergized, allowing the contact member 6' to drop, but as the latch 20 is interposed in way of the latch 21, the fingers 15' though they break contact with their post 13', similar to 13, will not be allowed to travel far enough to contact with the contact member 7' through its post 14'; therefore, when the train continues on its way and has passed out of the block A so that current in the block A is no longer shunted and the solenoid 5 is energized, picking up the contact member 6, the signal will not operate as friction or pressure between the toe of the member 21 and the arcuate edge of the member 20 will keep these members from moving and prevent the contact member 6' from closing its circuit with the post 14'. But it will readily be seen that as soon as the solenoid 5 lifts the contact member 6, breaking the contact between the members 6 and 7, through the finger 15 and post 14, the signal will stop operating. It will be understood that as soon as the train has passed completely out of the block B that as there is no longer a shunting of the battery 4', the solenoid 5' will pick up its contact member 6', relieving the pressure or friction between the latch members 20 and 21 and they will drop into inoperative or free position as they were before the train entered the block A.

It will, of course, be understood that a like operation occurs with the train coming in the opposite direction and entering block B first before entering block A.

It will also be seen that if there is any failing of the system due to failure of the batteries 4 or 4', or an accidental shunting between the rails, that a warning signal will still be given, as there is an actuation of a part of the device.

It is understood that the embodiment of the device and system shown is merely by way of illustration and not limitation, as other embodiments will readily occur to those skilled in the art.

I claim:

1. An interlocking relay having in combination a plurality of solenoids, members co-operating with said solenoids and controlled

thereby for controlling electric circuits, and two gravity latches freely pivoted about different axes and adapted to be moved toward each other for locking purposes, and a lug on each latch positioned on the side away from the other latch for holding said latch in operative position.

2. An interlocking relay having in combination a plurality of solenoids, members operating with said solenoids and controlled thereby for controlling electric circuits, said members including a plurality of fingers and means carried by said fingers adapted to operate interlocking latches, said latches provided with latch-engaging toes, and a short lug on each latch positioned on the side away from the other latch for holding said latch in operative position.

3. An interlocking relay having in combination a plurality of solenoids, members operating with said solenoids and controlled thereby for controlling electric circuits, and latches freely pivoted about different axes and adapted to be moved toward each other for locking purposes to prevent operation of one of said members under certain conditions, and a short lug on each latch for holding said latch in operative position.

4. In an interlocking device for a relay, the combination of gravity latches freely pivoted about separate axes and adapted to be moved toward each other for locking purposes, arcuate portions terminating in latch-engaging toes, and a lug on each latch positioned on the side away from the other latch for holding said latch in operative position.

5. In a device of the character described, the combination of members adapted to be operated in sequence, means preventing operation of one of said members after the other of said members has been operated, said means comprising interlocking latches and a short lug on each latch for holding said latch in operative position.

45 6. In a device of the character described, the combination of members adapted to operate external means, said members being adapted to be operated in sequence and means operated by each of said members for preventing operation of one of said members after the other of said members have been operated, said means comprising interlocking latches and a short lug on each latch positioned on the side away from the other latch for holding said latch in operative position.

7. In a device of the character described, the combination of members adapted to operate external means, said members being adapted to operate in sequence and means carried by said members for operating interlocking latches for preventing operation of one of said members after the other of said members have been operated.

65 8. A latch for interlocking relays having

a pivot opening, an edge lying in an arc about said opening, and a short lug so arranged that the latch may be caused to pivot by co-action between said lug and an external member.

9. A latch for interlocking relays having a pivot opening, an edge lying in an arc about said opening and extending to one side thereof, and a short lug projecting from said latch on the other side of said latch.

10. A latch for interlocking relays having a vertically extending shank with a pivot opening near the top thereof, a toe extending horizontally from the bottom thereof, and a short lug projecting from near the top of the other side of said shank, said toe having its bottom edge lying in an arc about said opening.

11. An interlocking relay having in combination a plurality of solenoids, members cooperating with said solenoids and controlled thereby for controlling electric circuits, a latch support including two spaced pivots, a threaded extension on said support, an adjustment nut screwed on said extension for adjusting said support and a latch mounted freely on each of said pivots, one of said latches having an edge arcuate about its pivot and extending toward the other latch and a short lug extending outwardly in the opposite direction.

12. Interlocking apparatus for relays including a pair of latches pivotally mounted about spaced axes and in a common plane, one latch having an interlocking toe extending toward the other, said other having an edge arcuate about its pivotal axis and adapted to swing into the line of movement of said toe, and having a lug arranged to cause that latch so to swing, the extending portion being so shaped that the latches can contact only through the end of the toe of one or the other.

Signed at Chicago, Illinois, this 4th day of May, 1927.
